UNITED STATES PATENT OFFICE.

JAMES MURPHY, OF CHICAGO, ILLINOIS, ASSIGNOR TO THE PROVIDENT FURNACE COMPANY, OF SAME PLACE.

DESIGN FOR A FURNACE-TILE.

SPECIFICATION forming part of Design No. 34,552, dated May 21, 1901.

Application filed January 12, 1901. Serial No. 43,079. Term of patent 14 years.

To all whom it may concern:

Be it known that I, JAMES MURPHY, a citizen of the United States, residing at Chicago, in the county of Cook and State of Illinois, 5 have invented and produced a new and original Design for a Furnace-Tile; and I hereby declare the following to be a full, clear, and exact description thereof, reference being had to the accompanying drawings, forming a part

hereof.

In the drawings, Figure 1 is a view in perspective of a tile embodying my new and original design; Fig. 2, a broken vertical section taken as indicated at line 2 of Fig. 1 and 5 Fig. 3 a horizontal section taken as indicated at line 3 of Fig. 1.

As shown in the drawings, the leading or material feature of my design consists of a

tile A of rectangular cross-section, having a vertical channel a located near the outer portion of the tile, a half-circular perforation a' intersecting the channel a at the upper portion thereof, a half-circular perforation a^2 of larger diameter and having its center nearer the inner or fire surface of the tile, and a discharge - orifice a^3 , having an inclined lower wall a^4 .

What I claim as new, and desire to secure by Letters Patent, is—

The design for a furnace-tile herein shown 30 and described.

JAMES MURPHY.
